JOHN H. SHEPHEARD,

By *William H. Low*
Attorney.

UNITED STATES PATENT OFFICE.

JOHN H. SHEPHEARD, OF ALBANY, NEW YORK, ASSIGNOR OF ONE-HALF TO
ROBERT C. BLACKALL, OF SAME PLACE.

ROD FOR SLIDE-VALVES.

SPECIFICATION forming part of Letters Patent No. 519,458, dated May 8, 1894.

Application filed September 24, 1892. Serial No. 446,833. (No model.)

To all whom it may concern:

Be it known that I, JOHN H. SHEPHEARD, of the city and county of Albany, in the State of New York, have invented new and useful Improvements in Rods for Slide-Valves, &c., of which the following is a specification.

This invention relates to improvements in rods for slide-valves, pistons, and other similar parts of a steam-engine which, by constant motion through the packing of stuffing-boxes, become quickly worn and reduced in diameter so as to require renewing, thereby involving a considerable loss in time and expense.

To remedy this defect, my invention consists in providing each rod with a removable sleeve which will surround the rod and, being exposed to the wearing action of the packing, will leave the rod intact and preserve the strength required to meet the strain to which it is subjected.

In the accompanying drawings, which are herein referred to and form part of this specification, Figure 1 is a plan view of a slide-valve rod adapted to use on a locomotive engine. Fig. 2 is a side elevation of the same with parts shown in longitudinal section. Fig. 3 is a plan view of the valve-rod detached from the rocker-arm connection and without the removable sleeve. Fig. 4 is a detached plan view of the rocker-arm connection; and Figs. 5, 6 and 7 are detached views of the removable sleeve, its adjusting-nut and jam-nut.

As represented in the drawings, A designates a valve-rod of the character commonly used on locomotive engines, the same being provided with a yoke, 1, fitted to contain the slide-valve of an engine; the outer end of said rod is provided with the usual taper shank, 2, having a key-hole, 3, formed therein. At the junction of said rod and yoke, a coniform hub, 4, is preferably made for the purpose of providing a steam-tight joint for the removable sleeve at that point.

B designates a removable sleeve that is fitted to slide freely on the rod A, and preferably said sleeve is made of steel-tubing so that it can be hardened if required. The inner end of said sleeve is fitted to the hub 4, and preferably said sleeve is fitted to the hub by means of a ground-joint so as to render

the joint steam-tight, but, when preferred, any other form of joint may be used. At the outer end of the sleeve a screw-threaded portion, 5, is provided for receiving an adjusting-nut, 6, by which said sleeve can be forced against the hub 4, and a jam-nut, 7, which bears against the inner end of said adjusting-nut to prevent the latter from working backward on said sleeve.

C designates a rocker-arm connection of the form commonly employed on locomotive engines. One end of said connection is provided with a hub, 8, which is bored to receive the wrist-pin of the rocker-arm, and at the opposite end of the connection a socket, 9, is formed to fit the shank 2 of the valve-rod. The socket 9 is provided with a key-hole, 10, which is arranged to correspond to the key-hole in the shank 2. A tapered cotter or key, 11, is fitted to pass through the key-holes 3 and 10 and draw the shank 2 snugly into the bore of the socket 9.

My invention is operated in the following manner: The sleeve B is slipped onto the rod A, the nuts 6 and 7 being screwed onto said sleeve so as to leave space for adjusting the nut 6, and the connection C is keyed to the rod A in the usual manner; then the nut 6 is turned to carry said nut into contact with the end of the socket 9 and force the inner end of the sleeve into close contact with its seat on the hub 4, thereby preventing steam from escaping through said sleeve, and the nut 7 is then screwed up into close contact with the nut 6, so as to prevent the latter from working back-away from the end of the socket 9—and leaving the sleeve free to acquire a slight endwise movement; thereby a space would be left between the inner end of the sleeve B and hub 4 to permit the steam to escape therethrough and, by passing between the bore of the sleeve and periphery of the rod, pass off at the outer end of the sleeve, but, by keeping the nut 6 in close contact with the end of the socket 9, this escape of the steam can be entirely prevented.

My invention can be readily applied to piston-rods or other rods that are required to work through packing in stuffing-boxes in order to obtain a tight joint around them before they emerge from the packing, but when

applied to piston-rods, or other rods which have but little clearance between the stuffing-box and the socket in which the outer end of the rod is secured, I prefer to cut a screw-thread in the bore of the sleeve and screw the adjusting-nut into said screw-thread; in such cases the adjusting-nut is formed with a screw-threaded sleeve that projects from one face of said nut and is fitted to screw into the removable sleeve, and the jam-nut is fitted to screw onto said adjustable-nut and bear against the outer end of the removable sleeve.

What I claim as my invention, and desire to secure by Letters Patent, is—

15 A reciprocating-rod having at or near its

inner end an abutment; its outer end being fitted to couple to a socket, a socket removably secured to said rod, a removable-sleeve fitted to surround the periphery of said rod and to take against said abutment; the outer end of said sleeve having a screw-thread formed on its periphery, and a nut fitted to screw onto said screw-thread and to take against the inner end of said socket, as and for the purpose specified.

JOHN H. SHEPHEARD.
